CLAIM

The ornamental design for an accessory hook as shown and described.

DESCRIPTION

FIG. 1 is a perspective view of the accessory hook of our design;

FIG. 2 is a rear elevation of the accessory hook of FIG. 1;
FIG. 3 is a top plan view of the accessory hook of FIG. 1;
FIG. 4 is a right side elevation of the accessory hook of FIG. 1;

FIG. 5 is a front elevation of the accessory hook of FIG. 1;
FIG. 6 is a left side elevation of the accessory hook of FIG. 1; and,
FIG. 7 is a bottom plan view of the accessory hook of FIG. 1.

Features shown in broken lines are for illustrative purposes only and form no part of the claimed design.
